UNITED STATES PATENT OFFICE.

ALFRED VIKTOR SUCHY, OF NIAGARA FALLS, NEW YORK, ASSIGNED TO NIAGARA ALAKALI COMPANY, OF NIAGARA FALLS, NEW YORK, A CORPORATION OF NEW YORK.

BLEACH-CHAMBER.

1,126,586.

Specification of Letters Patent.

Patented Jan. 26, 1915.

Application filed January 22, 1914. Serial No. 312,715.

To all whom it may concern:

Be it known that I, ALFRED V. SUCHY, a subject of the Emperor of Austria-Hungary, residing in Niagara Falls, New York, have invented certain Improvements in Bleach-Chambers, of which the following is a specification.

The object of my invention is to so construct a bleach chamber, such as that employed in the preparation of chlorid of lime or bleaching powder, as to provide in a simple and inexpensive way for the cooling of the floors of the chambers upon which the lime is deposited for the action of the chlorin gas. This object I attain in the manner hereinafter set forth, reference being had to the accompanying drawings, in which—

Figure 1 is a partial transverse section of a bleach chamber structure constructed in accordance with my invention, and Fig. 2 is a partial longitudinal section of the same.

The roof and floors of my improved bleach chamber structure are composed of concrete formed with suitable stiffening girders and mounted upon suitable columns, and the outer walls may also be composed either wholly of concrete or of concrete and brick, as desired. The structure which I have shown in the drawing has four compartments 1, 2, 3, and 4, but my invention is shown only as applied to the intermediate compartments 2 and 3 and consists in constructing these compartments with a double floor having transverse partitions 5 between the upper and lower members of the floor so as to properly stiffen the upper member, and with troughs 6 communicating with the ends of the spaces between the top and bottom members of the floors so that a body of water or other cooling fluid can be maintained in or caused to flow through said

spaces in order to insure the maintenance of the floor at the relatively low temperature which is desirable.

The compartments 2 and 3 are sealed by walls 7 of brick or other available material, from end gangways 8 and the chambers are also sub-divided by means of alleys 9 from which the sub-divisions are sealed by walls 10, the troughs 6 projecting into said alleys as shown in Fig. 1. The treating chambers may also be rendered impervious to chlorin gas by an internal coating of tar, or in any of the ways ordinarily used for that purpose.

When it is desired to cause a circulation of the cooling fluid through the spaces of the floors said fluid may be withdrawn from the trough at one end of the floor as a fresh supply is introduced into the trough at the other end of the floor.

I claim:

1. A bleach chamber having a double floor with troughs at the ends of the same whereby a body of cooling fluid can be maintained between the upper and lower members of the floor.

2. A bleaching chamber structure having the bleaching chambers flanked by alleys, said bleaching chambers having double floors with end troughs communicating with the spaces between the top and bottom members of the floors and projecting into said alleys.

In testimony whereof, I have signed my name to this specification, in the presence of two subscribing witnesses.

ALFRED VIKTOR SUCHY.

Witnesses:

E. M. SERGEANT,
H. L. WHITNEY.
